SUSPENDERS

Frank J. Lozo, Saskatoon, Saskatchewan, Canada

Application May 2, 1940, Serial No. 333,047

1 Claim. (Cl. 241—18)

This invention relates to an improvement in the construction of garment suspenders and aims particularly to provide improved means for connecting the front diverging ends of a pair of shoulder straps to pairs of button straps to permit the shoulder straps and button straps to adjust automatically relatively to each other to prevent the supported garment from being distorted where the hang of the garment does not naturally correspond to the normal angle of support of the suspenders.

More particularly, it is an aim of this invention to provide a pair of suspenders for trousers having means for swivelly connecting button straps to the shoulder straps to permit automatic adjustment of the parts relatively to each other so that the trousers may hang naturally and so that the front crease of the trousers will not be distorted.

Still a further aim of the invention is to provide improved means for connecting the shoulder straps and button straps including pairs of plates having co-acting means for swivelly connecting the plates of each pair, said means being readily detachable for detaching the suspenders from the trousers without removing the button straps.

Still another object of the invention is to provide improved means for adjustably and detachably connecting corresponding ends of pairs of button straps to the corresponding plates of said pairs of connecting plates to position the straps in diverging relationship relatively to each other.

Other objects and advantages of the invention will hereinafter become more fully apparent from the following description of the drawing, which illustrates a preferred embodiment thereof, and wherein:

Figure 1 is a fragmentary top plan view of a pair of suspenders showing a pair of the connecting plates assembled and connecting a shoulder strap to a pair of button straps.

Figure 2 is an enlarged top plan view showing the invention assembled and similarly connected to the button straps and a shoulder strap,

Figure 3 is a side elevational view of the parts as shown in Figure 2,

Figure 4 is a longitudinal sectional view taken substantially along the plane of the line 4—4 of Figure 2,

Figure 5 is a top plan view of one of the pair of connecting plates, and

Figure 6 is a similar view of the other plate.

Referring more particularly to the drawing, wherein like reference characters designate like

or corresponding parts throughout the different views, 10 designates generally a portion of a pair of suspenders having their diverging free ends looped at 12 and provided with the conventional slide clamps 13 for adjusting the length of the loops 12 and of the shoulder straps 11. These parts are of conventional construction and are illustrated for the purpose of illustrating the application of the invention, designated generally at 14, and which will hereinafter be described.

The invention, designated generally 14, comprises a pair of connecting plates for connecting a looped end 12 of a shoulder strap 11 to a pair of button straps 15 which are provided adjacent their free ends with buttonholes 16 for engaging a pair of spaced buttons, not shown, on the front portion of a pair of trousers, not shown, or other garment to be supported by the suspenders 10.

20 The pair of connecting plates 14 includes the plates 16 and 17 the former of which is provided adjacent its upper edge with a slot 18 for engaging the loop 12 to thereby connect the plate 16 to one of the shoulder straps 11. Below the slot 18, the plate 16 is provided with an outwardly projecting lug 19 having a triangular shaped head 20 and a restricted shank 21. As best seen in Figure 5, head 20 is disposed so that one side of its triangle is transversely of the plate 16 and adjacent its lower edge.

25 Plate 17 adjacent its upper end, is provided with a triangular shaped opening 22 of sufficient size for the passage of the head 20. One side of the opening 22 is disposed transversely of the plate 17 and adjacent its upper edge. Plate 17 is also provided with two rows of spaced slots 23 and said rows being disposed in downwardly diverging relationship relatively to each other and with each of said slots extending outwardly and upwardly relatively to the side edges of the plate 17. As best seen in Figure 6, the lower edges of the upper slots and the upper edges of the lower slots are toothed at 24, for a purpose which will hereinafter be apparent.

30 From the foregoing it may be seen, that the ends of the button straps 15, opposite to the ends provided with the button-holes may be passed upwardly through the lower slots 23, from the back of the plate toward the front of the plate, back through the upper slots 23, back again to the front of the plate through the intermediate slots and then out to the rear through the lower slots. The toothed edges 24 will prevent these upper ends of the straps 15 from slipping when

the suspenders 10 are in use while the length of the straps may be adjusted, as desired.

It is to be understood that the other shoulder strap 11 will be provided with a similar connector 14 and it will be apparent that when these pairs of connectors 14 are assembled, as in Figures 1 to 4, the plates 16 and 17 will be swivelly mounted relatively to each other and may angularly adjust themselves relatively to each other, automatically, to equalize the pull on the pairs of button straps 15 so that the suspenders 10 will not distort the hang of the garment to which it is connected. Since the triangular head 19 is disposed so that its points are disposed above the sides of the triangular opening 22, when the plates 16 and 17 are in an extended position relatively to each other, the plates will not be accidentally disconnected since the swing of the plates relatively to each other will not be sufficient to align the head 20 with the opening 22. However, the suspenders 10 may be readily disconnected from the front of the garment to which it is attached by turning the plate 17 in either direction until the head 20 aligns with the opening 22 after which the plate 17 may be pulled outwardly relatively to the plate 16 to cause the head 20 to pass through opening 22 thus disengaging the pairs of plates

and disengaging the suspenders from the front of the garment.

Various modifications and changes are contemplated and may obviously be resorted to as 5 only a preferred embodiment of the invention has been illustrated and described.

I claim as my invention:

A connecting means for suspender shoulder straps and suspender button straps, comprising 10 pairs of connecting plates, each of said pairs of plates including a plate connected to an end of a shoulder strap and having an outwardly projecting stud provided with a triangular shaped head, the other plate being connected to a pair of button straps and being provided 15 with a triangular shaped opening for the passage therethrough of the head, said head and opening being out of registry when the plates are in normal extended positions relatively to each other, one corner of the head being arranged to point toward the remote end of the first mentioned plate, and one corner of the opening being arranged to point toward the remote end of the last mentioned plate whereby one of the 20 sides of the opening will normally engage and rest upon said stud.

FRANK J. LOZO.
